UNITED STATES PATENT OFFICE.

THOMAS G. LOVEGROVE, OF PHILADELPHIA, PENNSYLVANIA.

MATCH BOX.

Application filed December 21, 1920. Serial No. 432,232.

To all whom it may concern:

Be it known that I, THOMAS G. LOVEGROVE, a citizen of the United States, residing in the city and county of Philadelphia, 5 State of Pennsylvania, have invented a new and useful Match Box, of which the following is a specification.

My invention consists of a match box more particularly formed of metal, whose 10 cover is provided with a passage which is adapted to direct a match to be struck to the striking surface in the body of the box, and to prevent the ignition of the matches in the box by the head of a match that is 15 struck flying off from what may be termed the stick of the match, said passage having its wall provided with inclined flanges which extend to said surface and serve to direct the head of the match that is struck to the 20 exterior of the cover of the box without liability to catch on the said wall or lodge on the striking surface and clog the joint of said surface and wall.

It consists also in providing the box with 25 a receptacle for car tickets and other articles; the members of said receptacle being preferably component parts of the adjacent portion of the box.

The invention is satisfactorily illustrated 30 in the accompanying drawing, but the important instrumentalities thereof may be varied, and so it is to be understood that the invention is not limited to the specific details shown and described, as long as they 35 are within the spirit or scope of the claims.

Figures 1 and 2 represent perspective 40 views of opposite sides of a match box embodying my invention.

Figure 3 represents an elevation of the 45 box in open condition.

Figure 4 represents a transverse section on line 4—4 Figure 1, on an enlarged scale.

Figure 5 represents a longitudinal section on line 5—5 Figure 1 on an enlarged 50 scale.

Figure 6 represents a top or plan view of the box shown in either Figures 1 or 2.

Similar numerals of reference indicate 55 corresponding parts in the figures.

Referring to the drawings.

1 designates a casing consisting of the body 2 and lid or cover 3, the latter being hinged at one end to the adjacent end of the casing and the casing having at the other end the catch 4 whose nose is adapted to engage the eye 5 on the relative end of the cover where-

by the latter may be held in closed position, it being noticed that the body is adapted to receive the matches 6 which are of the form of a batch connected with the pad 7, 60 the latter being retained in position by the lips 8 which are connected with the sides of the interior of the body and adapted to embrace the sides of said pad, the latter having thereon the match-striking surface 9 65 as usual in such cases.

In the outer face of the cover 3 is the passage 10 which is over said striking surface 9, whereby when the box is closed said surface is exposed and so may have a match 70 struck thereon.

It will be seen that when a match is required, the cover is opened and the match is accessible when it may be removed. Then the cover is closed and the match may be 75 struck, when as the matches remaining in the box are covered or guarded their heads are prevented from being ignited by the head of the match that is struck should said head fly-off which is known to occur occasionally 80 when the matches in the box are unguarded.

The walls of the passage are continued inwardly from the outer face of the cover forming the flanges 11 which project towards the striking surface 9 and engage 85 therewith, said flanges on the respective sides of the walls of the passage converging so as to incline outwardly from the striking surface whereby when a match is struck by being moved laterally over said surface 90 its head will ride upon either of said inclined flanges 11 to the exterior of the passage 10 and consequently beyond the exterior of the outer face of the cover without liability to lodge on the wall of the 95 passage and clog the joint between said wall and the striking surface and deposit on the latter.

On what may be termed the bottom or back of the body of the box is the receptacle 12 which is formed in the present case by striking up from said back so as to produce the outturned sides 13, the outer wall 14, the closed bottom 15, and the open top 16, the latter constituting the inlet to the 100 interior of said receptacle, it being noticed that as the metal or material of the back of the box is struck up or swedged out it forms said sides, outer wall and bottom, and thus the receptacle is integral with said 105 back, while the metal or material as struck up or swedged out forms an opening in the 110

back and thus the receptacle adds no weight to the body of the box. The opening formed in the back is closed by the batch of matches which latter thus prevent objects from entering the body of the box.

It is evident that the sides, outer wall and bottom of the receptacle 12 may be brazed, soldered or otherwise secured to the back of the body. The receptacle provides convenient means for containing car or other tickets or articles which are readily removable at the open top 16 of the receptacle.

Having thus described my invention what I claim as new and desire to secure by Letters Patent, is:—

1. A match box consisting of a body and a cover therefor, said body being adapted to contain therein matches and a match-striking surface, said cover being hinged at one end to said body and having therein near the other end thereof a passage which is adapted to form a communication with and expose said match-striking surface, the walls of said passage being continued inwardly toward the striking surface.

2. A match box consisting of a body having an opening in the back, and a cover therefor, said body being adapted to contain therein matches and a match-striking sur-

face, said cover having therein a passage which is adapted to form a communication with, and expose said match-striking surface, and an inclined flange on the wall of said passage extending inwardly from said cover to said surface and adapted to guide the head of a struck match from said surface over the flange.

3. A match box consisting of a body and a cover therefor, and a receptacle on the exterior of the box, the same being formed of a front, sides and bottom walls and having an inlet to its interior, said walls being connected with the adjacent portion of the box and projecting outwardly therefrom to form an open back adapted to be closed by the matches.

4. In a match box having a body and a cover, said body having an opening in the back and forming a receptacle on the exterior of the box formed of outwardly projecting walls on the adjacent portion of the box and comprising component parts of said portion, the receptacle having an inlet to the interior thereof.

THOMAS G. LOVEGROVE.
